UNITED STATES PATENT OFFICE.

WILLIAM J. REGAN, OF WILKINSBURG, PENNSYLVANIA, ASSIGNOR TO THE McCONWAY & TORLEY COMPANY, OF PITTSBURGH, PENNSYLVANIA, A CORPORATION OF PENNSYLVANIA.

DRAFT GEAR.

Application filed June 2, 1923. Serial No. 642,833.

To all whom it may concern:

Be it known that I, WILLIAM J. REGAN, a citizen of the United States, residing at Wilkinsburg, in the county of Allegheny and State of Pennsylvania, have invented certain new and useful Improvements in Draft Gears; and I do hereby declare the following to be a full, clear, and exact description of the invention, such as will enable others skilled in the art to which it appertains to make and use the same.

My invention relates to draft gear for railway cars and particularly to the type employing a cushioning unit involving friction elements. The primary object of the invention is to provide a strong and simple mechanism which may efficiently cooperate with the parts of the car with which it is associated.

20 A principal feature of the invention, generally stated, consists in constructing a draft gear with a yoke device formed with a casing and having a pair of horizontally aligned slotted arms terminating at their rear ends in spaced relation to the forward end of the casing, the arms being integrally united in advance of the casing by vertically aligned webs which also are integrally united to the casing and serve to communicate to the latter the draft strains imparted to the said arms when the device is in service, the said casing having an opening at its rear end permitting the introduction of the elements of a cushioning unit and being provided with a detachable closure for said opening, and a follower which is adapted to be actuated by the car coupler upon a buffing movement of the latter being movably mounted between the said webs in advance of the casing and to the rear of the said arms.

45 A further feature of the invention consists in constructing a draft gear with a yoke device formed with a casing and having integrally united to the latter a pair of arms which are operatively attached to and receive between them a car coupler, the said casing having an opening at its rear end and being furnished with a removable closure member bridging the said opening when the parts are in assembled relation and being adapted to engage a back-stop rigidly secured to the sills of the car, the

said back-stop having a centrally disposed projection adapted to extend into the opening at the rear end of the casing so as to stand behind the closure member for the opening.

55 Other features of the invention involving particular details of construction and relations of parts will hereinafter appear and be pointed out in the claims.

60 In the drawings illustrating the best mode in which I contemplate applying the principle of the invention,—

65 Figure 1 is a view, partly in plan and partly in horizontal section, of a draft gear embodying the invention, stationary parts of the car with which it is associated being also shown.

70 Figure 2 is a vertical longitudinal section of the construction shown in Fig. 1, the car coupler being in elevation.

75 In the drawings, 1 indicates the stem of a car coupler and 2 is the yoke device. The coupler 1 and yoke device 2 are preferably connected by a horizontally extending key 3, the arrangement being such that the coupler is capable of moving rearwardly with respect to the yoke device during a 80 buffing operation. The yoke device is formed with a hollow casing 4 made of any desired shape and size suitable for receiving and cooperating with the springs and friction elements of the cushioning unit housed thereby, the cushioning unit being diagrammatically indicated in the drawings by the diagonal dotted lines 5 in the conventional manner.

85 The rear end of the casing is formed with a centrally disposed opening 6 providing means for the ready introduction of the elements of the cushioning unit. This opening is bridged by a removable closure member or plate 7 which preferably is retained in assembled position by extending into slots 8 formed in the casing slightly in advance of the rear end of the latter. When the device is in service the center sills or draft sills 9 of the car retain the closure member 7 in proper relation to 90 the casing 4.

95 The rear end of the casing preferably cooperates with a back-stop 10 interposed between and rigidly secured to the sills 9 of the car. This back-stop may advantageously be provided with a centrally dis-

posed forwardly extending projection 11 adapted to extend into the opening 6 of the casing and to engage the plate 7 by which said opening is bridged. By this means the 5 removable closure member 7 is well supported against bending during buffing operations and concentration of the buffing forces on the areas of the rear end of the casing engaging the back-stop is avoided.

10 The yoke device has a pair of horizontally aligned arms 12 between which the rear end of the stem of the coupler 1 is received and to which draft strains are transmitted from the coupler through the connecting 15 key 3. These arms, which preferably are spaced apart a distance somewhat greater than the width of the interposed portion of the coupler and are provided with elongated slots 13 in which the key 3 travels 20 rearwardly in buffing, terminate in advance of the forward end of the casing 4 so as to afford space for the reception and operation of a follower 14 which is forced toward the casing 4 when the coupler 1 25 performs a buffing operation. The slotted arms 12 are integrally united in advance of the casing by vertically aligned webs 15 which also form integral connections with the casing 4. The webs 15 preferably extend forwardly only substantially to the outer ends of the slots 13 and their forward portions may, as shown, converge toward said slots.

30 The follower 14 is movably mounted between and projects laterally beyond the webs 15 in interposed relation to the coupler 1 and the forward end of the casing 4. When the coupler is disconnected from the yoke device the arms 12, whose rear ends extend 35 across the forward face of the follower 14, provide means carried by the yoke device for limiting the forward movement of the follower so as to retain it in assembled relation to the casing 4 and the cushioning unit 40 contained therein. The outer ends of the follower are adapted to cooperate in draft with follower stops or draft lugs 16 securely riveted to the sills 9. The follower stops and the sills 9 are provided with slots 45 17 allowing the coupler connecting key 3 to travel back and forth with the coupler. The key 3, which is preferably provided at one end with a lug or head 18, may conveniently be retained in assembled position in 50 a well known manner by means of a collar or washer 19 and a cotter 20.

55 By my invention a combined draft yoke and friction casing formed as an integral casting may be provided without unduly increasing the size of the device, while yet enabling the friction casing to be made of comparatively great length.

I claim:—

60 1. A draft gear involving a yoke device provided with a casing and having a pair of

horizontally aligned slotted arms terminating at their rear ends in spaced relation to the forward end of said casing, said arms being integrally united in advance of said casing by vertically aligned webs extending 70 forwardly from and integrally united to said casing and adapted to transmit draft strains from said arms to said casing, said webs converging at their forward ends and terminating adjacent the forward ends of the slots 75 of said arms, a follower movably mounted between said webs in advance of said casing and to the rear of said arms, a car coupler extending between said arms and movable longitudinally with respect to said yoke device, and a key operatively connecting said coupler and arms for transmitting draft strains to the latter, said casing having an opening at its rear end and being provided with a detachable closure for said opening. 80 85

2. A draft gear involving a yoke device provided with a casing and having a pair of oppositely disposed arms provided with aligned key receiving slots, said arms terminating at their rear ends in advance of said 90 casing and in spaced relation to the latter and being integrally united to said casing and to each other by spaced webs adapted to receive the stem of a car coupler between them, said casing having an opening at its rear end and being provided with a detachable closure for said opening, a car coupler extending between said arms and webs and movable longitudinally with respect thereto, 95 a key extending through said coupler and through said slotted arms for transmitting draft strains from said coupler to said yoke device, and a follower movably mounted between and projecting beyond said webs in interposed relation to said coupler and the forward end of said casing, said arms being adapted to limit longitudinal movement of 100 said follower away from said casing. 105

3. A draft gear involving a yoke device provided with a casing and having a pair of arms adapted to receive the stem of a car coupler between them, said arms being integrally united to said casing and having aligned key receiving slots, a car coupler extending between said arms and movable 110 longitudinally with respect thereto, a key extending through said coupler and entering the slots of said arms, and a follower in advance of said casing movably mounted between and projecting laterally beyond said arms, said casing having an opening at its rear end and being slotted adjacent said opening to receive a plate forming a removable closure for said opening. 115 120

4. A draft gear involving a yoke device 125 provided with a casing and having a pair of arms adapted to receive the stem of a car coupler between them, said arms being rigidly united to said casing and having aligned key receiving slots therein, a car coupler 130

extending between said arms and movable longitudinally with respect thereto, and a key extending through said coupler and said slots for transmitting draft strains to said arms, said casing having an opening at its rear end and being provided with a removable closure member bridging said opening

and being adapted to engage a back stop which is carried by the sills of the car and is provided with a centrally disposed projection adapted to extend into said opening behind said closure member. 10

In testimony whereof I affix my signature.

WILLIAM J. REGAN.
